(57) **CLAIM**

The ornamental design for a pair of footwear articles, as shown and described.

DESCRIPTION

FIG. 1 is a right-front perspective view of one article of a pair of footwear articles, showing our new design;

FIG. 2 is a left-front perspective view of the footwear article of FIG. 1;

FIG. 3 is a right-rear perspective view of the footwear article of FIG. 1;

FIG. 4 is a left-rear perspective view of the footwear article of FIG. 1;

FIG. 5 is a front view of the footwear article of FIG. 1;

FIG. 6 is a rear view of the footwear article of FIG. 1;

FIG. 7 is a left side view of the footwear article of FIG. 1;

FIG. 8 is a right side view of the footwear article of FIG. 1;

FIG. 9 is a top plan view of the footwear article of FIG. 1;

FIG. 10 is a bottom plan view of the footwear article of FIG. 1; and,

FIG. 11 is a cross sectional view of the footwear article taken along line 11-11 of FIG. 10.

The drawings show the design of a footwear article suitable for being worn on a left foot.

The ornamental design also includes the mirror images of drawings, i.e., the design of a footwear article suitable for being worn on the right foot. The broken lines in the drawing views depict portions of the pair of footwear articles that form no part of the claimed design.
